UNITED STATES PATENT OFFICE.

HAROLD F. ADAMS, OF FLUSHING, NEW YORK.

HONING DEVICE.

1,283,613.

Specification of Letters Patent.

Patented Nov. 5, 1918.

Application filed October 10, 1916. Serial No. 124,753.

To all whom it may concern:

Be it known that I, HAROLD F. ADAMS, a citizen of the United States, residing at Flushing, in the county of Queens and State 5 of New York, have invented a new and useful Honing Device, of which the following is a specification.

My invention relates to devices for honing cutlery, and it has for its object to provide a 10 simple, inexpensive, convenient and effective device to hold a knife blade at the proper angle when honing or whetting it. The pen knife is in almost universal use, yet few persons know the proper way to lay it on the 15 stone when whetting it, or have the skill to hold it steadily at the proper angle while rubbing it over the stone; and as a consequence of such lack of knowledge and skill, the great majority of pocket knives usually 20 have their edges in an unsatisfactory condition. I have provided an extremely simple attachment by the use of which even an inexperienced and unskilful person can whet his knife properly.

25 To the above ends, my invention consists in the device or attachment hereinafter described and claimed.

In the accompanying drawings,

Figure 1 is an enlarged isometric view of 30 my honing device, detached;

Fig. 2 is a side view of a pocket knife having my honing device mounted on the blade thereof; and

Fig. 3 is an enlarged cross-section of a 35 knife blade, with my device mounted thereon and lying on the hone or stone in position for whetting.

My honing device 10, in the form here 40 shown, consists of a strip of spring metal, preferably steel, bent along its length into an open ended tube having such a form that the two edges of the strip come together, or approximately so, forming a slit 11 between said edges. The corners may be cut away at 45 one or both ends, to form an entering notch 12. When the device is to be used, the blade 13 of the knife is inserted into or thrust lengthwise through the tube 10, with the back of the blade inside the tube and the 50 blade projecting through the slit 11, so that the edge of the blade is outside of the tube, as shown in Figs. 2 and 3. To insert the blade, the point thereof is started in the notch 12, and the tube 10 is then forced 55 lengthwise over the blade, which wedges its

way into the slit 11. The tube is held on the blade by its own resilience.

The tube 10 is of such form and size that, when said tube and the knife blade are laid on a hone 14, as shown in Fig. 3, the blade 60 will be held at an angle suitable for honing. It will be understood that the form of said tube can be varied. Said tube is shown of cylindrical form, which is perhaps preferable as being the simplest and as being pleasing to handle; but other forms can be employed, so long as the shape is such as to hold the back of the blade at a suitable elevation when laid on the hone.

It will be understood that my attachment 70 is not a handle by which to hold a blade to be sharpened, but is a guide to be mounted on a blade having its own handle 15.

The precise angle at which the blade will 75 be held on the stone, will depend upon the relation between the width of said blade and the diameter of the cylinder 10, if the tube is cylindrical; and, with any given tube, said angle will vary more or less with blades of different widths. A very wide blade will require a tube of greater diameter than a very narrow blade. I have found, however, that a single tube can be used with blades differing more or less in width without any serious departure from good practice.

At least one end of the tube 10 is preferably beveled off, this being accomplished in the present instance by making the notch at that end of suitable depth and shape to produce inclined edges 16. When the knife 90 blade to be sharpened has a rounded point, the tube is so placed on said blade as that the bevel or slant 16 bears approximately the same relation to the curved part of the edge of the blade that the straight part of 95 the tube does to the straight part of said edge. Said straight part of the edge is whetted by laying the blade and tube flat on the stone as shown in Fig. 3, and the curved part of the edge is whetted by suitably tilting the knife up endwise, the angle between the blade and the stone being determined by the bevel 16, which now rests against said stone.

In Fig. 2 the left hand end of the tube 10 105 is shown reaching entirely to the end of the sharp part of the blade, but this is not necessary. In other words, the tube can be shorter than shown.

It will be perceived that my honing at 110

2
tachment is very simple, and inexpensive, that it is convenient and effective in operation, and is small and can be readily carried in the pocket or kept with the hone ready 5 for use when needed.

Having thus described my invention, what I claim as my invention and desire to secure by Letters Patent is:

10 A honing attachment for knife blades having curved ends, said attachment consisting of a tube having a straight part with a longitudinal slit for the purpose set forth,

and said tube being beveled off at one end on opposite sides of said slit to guide the blade to control the honing of said curved end of 15 said blade, the guiding portion of the beveled end of the tube being spaced from the curved end of the blade to give substantially the same angle on the hone as the straight portion.

20 In testimony whereof, I have hereunto affixed my signature.

HAROLD F. ADAMS.
